UNITED STATES PATENT OFFICE.

ALEX A. CLARKE, OF CHICAGO, ILLINOIS.

PORTABLE ELECTRIC SAW.

Application filed May 31, 1923. Serial No. 642,695.

This invention relates to new and useful improvements in portable electric saws.

The object of the invention is to provide a portable motor driven saw in the form of a hand tool which may be easily and skillfully handled by the workman.

Another object of the invention is to provide a tool having a self-contained electric motor and which may be slid along the work like an ordinary bench plane.

A further object of the invention is to provide a vertical revolving saw driven by the motor together with means for adjusting the saw with relation to the work without interrupting the driving of said saw.

An important object of the invention is to provide in connection with a vertical revolving saw an elongated housing having a flat work engaging base through which the work is exposed to the saw and whereby the depth of the cut of the saw may be accurately controlled.

A construction designed to carry out the invention together with other particular features will be hereinafter described.

The invention will be more readily understood from a reading of the following specification and by reference to the accompanying drawings, in which an example of the invention is illustrated and wherein:

Fig. 1 is a side elevation of the saw constructed in accordance with my invention,

Fig. 2 is a plan view of the same,

Fig. 3 is a horizontal cross sectional view taken on the line 3—3 of Fig. 1,

Fig. 4 is a side elevation of a modified form of the invention,

Fig. 5 is a plan view of the same,

Fig. 6 is a partial vertical sectional view of the front end of the saw,

Fig. 7 is a detail of the adjusting means,

Fig. 8 is a cross-sectional view taken on the line 8—8 of Fig. 7, and

Fig. 9 is a horizontal cross-sectional view taken on the line 9—9 of Fig. 4.

In the drawings the numeral 10 designates an elongated housing having vertical side walls 11 and a transverse partition 12. At the rear end of the housing a vertical handle 13 is mounted and the front end of the flat base 14 of the housing is extended. Within the housing between the partition and the rear wall is suitably mounted an electric motor 15 having its armature shaft extend-

ing forwardly through said partition and 55 having a beveled pinion 16 fastened thereon.

The pinion meshes with a beveled gear 17 mounted on a counter shaft 18 which is journaled in a bracket 19 carried by the base. A gear 20 having a greater diameter 60 than the gear 17, is fastened on the outer end of the shaft 18. An adjusting yoke 21 is journaled on the side walls 10' on trunnions 22, which latter are axially alined with the axis of the shaft 18 and the gear 20. 65

Slots 23 are cut in the side walls concentric to the trunnions and a saw shaft 24 extending across the housing and through the slots, is journaled in the lower ends of the yoke. A pinion 25 fastened on the shaft 24 meshes 70 with the gear 20 and is driven thereby. The pivot of the yoke being concentric to the gear 20 it is obvious that when the yoke is swung to raise or lower the saw shaft 24, the pinion 25 will constantly remain in mesh with the gear. By this arrangement the saw shaft may be adjusted without interrupting the transmission of motion thereto.

A slot 26 is formed in the base 14 and a circular saw 27 mounted on the shaft 24 is adapted to project through said slot and engage the work. The depth of the cut of the saw is regulated by its projection below the base. For holding the yoke in adjusted positions a central plunger 28 is mounted 80 in the bore of a handle 29 and placed under the tension of a coiled spring 30 confined in said handle. A toothed segment 31 concentric to the pivots of the yoke is mounted 85 on top of the housing in position to be engaged by the plunger, which has a reduced point for this purpose. A pin 32 passing through the plunger extends through slots 33 in the handle. By grasping the handle and engaging the pin with the fingers the plunger may be raised and the yoke swung to raise or lower the saw. An electric switch 34 is mounted in the handle 13 so as to be 90 easily operated by the workman for stopping and starting the motor. 95

Any desired attachments may of course be made to the housing. Owing to its broad flat base 14 the housing will remain level on the work and make for accuracy. Various changes in the parts as well as modifications and alterations may be made within the scope of the appended claims.

As an illustration of such modification I

have shown in Figs. 4 to 9 another form of the invention. This form includes a comparatively short housing 10' having upright side walls 11' and a dome 35 in which 5 the motor 15' is mounted vertically instead of horizontally as in the first instance. A handle 13' is connected with the housing and has a switch 34'.

Opposed vertical recesses or guides 36 10 are formed in the forward portions of the side walls and provided with vertical slots 23' in their bottoms for receiving a transverse saw shaft 24'. An upright yoke 21' straddles the housing and engages in the 15 guides and has a central handle 29'. The saw shaft is journaled in the lower ends of the yoke. A circular saw 27' is fastened on the shaft and projects through a slot 26' in the base 14' of the housing. For raising 20 and lowering the yoke the handle 29' is employed and this handle is mounted to rotate in the yoke as is shown in Fig. 7. On its lower end within the yoke the said handle has a disk 37 (Fig. 8) provided with 25 diametrically opposite ears 38 pivotally connected with the inner ends of detents 39 mounted on screws 40, whereby they are pivoted and suspended from the yoke. The detents have slots 41 receiving the screws so 30 as to be moved longitudinally. Vertical posts 42 mounted on top of the housing penetrate the yoke and are provided with teeth for receiving the ends of the detents, whereby the yoke is supported in the positions to 35 which it is adjusted vertically.

By turning the handle 29' in a counter-clockwise direction the detents are withdrawn from the teeth of the posts and the yoke may be adjusted vertically to raise or 40 lower the saw. When the handle is turned in a clockwise direction the detents are moved into the teeth and the yoke fastened in position. For driving the saw shaft a pinion 43 is mounted horizontally on the 45 lower end of the vertical armature shaft of the motor. This pinion drives a gear 44 which in turn drives meshing pinions 45 and 46 respectively. The pinion 46 is fastened to the bottom of a vertical worm 47 mounted 50 in a bracket 48 on upper side of the base 14'. A pinion 49 fastened on the saw shaft 24' meshes with the worm which latter is long enough to permit ample vertical adjustments of the saw shaft without disconnecting the 55 pinion from the worm.

In using the saw the operator grasps the handle 13' and moves the device onto the work. The saw may be set previously or it may be adjusted while engaging the work. 60 The whole device may be easily handled and moved into various positions.

What I claim, is;

1. In a portable electric saw, a housing, an elongated base under the housing having 65 a slot, a motor mounted in the housing, a

yoke at the exterior of the housing and vertically adjustable on the housing, a saw shaft carried by the yoke and extending through the housing, a saw mounted on the shaft within the housing and located to project 70 through the slot in the base, a driving connection between the saw shaft and the motor remaining constant during adjustments of the yoke, and means for fastening the yoke in adjusted positions. 75

2. In a portable electric saw, a housing, an elongated base under the housing having a slot, a motor mounted in the housing, a handle on one end of the housing, a yoke at the exterior of the housing and mounted to move 80 vertically on the housing, said housing having vertical slots, a transverse shaft carried by the yoke and extending through the slots of the housing, a vertical circular saw with in the housing and fastened on the shaft, a 85 pinion on the shaft, a train of gears between the motor and the pinion in constant engagement, and means for fastening the yoke in adjusted positions.

3. In a portable saw, the combination 90 with an elongated housing having a flat base and provided with a slot through the said base, of a shaft extending through the walls of said housing, the latter being slot- 95 ted for the reception of the ends of said shaft, a saw mounted on said shaft and adapted to be projected through the slot of the base, a motor within the housing, gearing connections between said motor and said shaft, an operating yoke at the exterior of 100 the housing and spanning the same, said yoke being connected to the ends of said shaft for adjusting the latter in the slotted sides of the housing, whereby to adjust the degree of projection of the saw through the housing, and means whereby said yoke may be held in adjusted position with respect to the housing. 105

4. In a portable saw, the combination 110 with an elongated housing having a flat base, the latter being provided with a slot, the sides of said housing also being provided with aligned slots, of a shaft extending transversely through the said housing and having its ends projecting through 115 the slots of the sides of the housing, a saw mounted on said shaft within the housing and adapted to be projected through the slot of the base, a motor located within said housing, a yoke arranged over the housing 120 and spanning the sides thereof, said yoke being connected to the projecting ends of said shaft, means for adjusting said yoke with respect to said housing to vary the degree of projection of the saw through the base, and gear connections between said motor and said shaft. 125

5. In a portable saw, the combination 130 with an elongated housing having a flat base, the latter being provided with a slot, the

sides of said housing being slotted, of a shaft arranged within said housing and projecting through the slotted sides thereof, a saw mounted on said shaft and adapted to be projected through the slot of the base, a yoke arranged at the exterior of the housing and spanning the sides thereof, said yoke being connected to the projecting ends of said shaft, said yoke being adjustable with respect to the housing, whereby to vary the degree of projection of the saw through the housing, means for locking said yoke in its positions of adjustment with respect to the housing, a motor located within the housing, and gearing connections between said motor and said shaft, said connections including provision for adjustment of the saw with respect to the housing without disturbing the driving relation of the motor to the saw in the different positions of adjustment of the latter.

which the ends of said shaft project, a motor arranged in the compartment in rear of said partition and having its armature shaft projecting through the partition, a saw mounted on said transversely extending shaft and adapted to be projected through the slot of said base, a U-shaped yoke spanning the outside of said casing and having its ends pivoted on the side walls thereof and connected with the projecting ends of said transverse shaft, whereby to vary the degree of projection of the saw through the slot of the base upon movement of said yoke with respect to the housing, a train of gearing arranged in the compartment wherein the saw is located and affording driving connections between said transverse shaft and the armature shaft of said motor, and means for locking the yoke in its different positions of adjustment with respect to the housing.

6. In a portable saw, the combination with a housing having an elongated base and provided with a slot therein, said housing being provided with a partition extending transversely thereof and forming compartments in the housing, a shaft extending transversely through one of said compartments, the walls of said compartment being provided with slots through which the ends of said shaft project, a motor arranged in one of the compartments of said housing and having its armature shaft projecting through said partition, a saw mounted on said transversely extending shaft and adapted to be projected through the slot of said base, a yoke spanning the outside of said casing and having its ends pivoted at the exterior of the casing and also connected with the projecting ends of said transverse shaft, whereby to vary the degree of projection of the saw through the slot of the base upon movement of said yoke with respect to the housing, means for locking the yoke in its different positions of adjustment, and gearing connections between said motor and said transverse shaft for driving the latter from the motor.

8. In a portable saw, the combination with a housing having an elongated base and provided with a slot therein, said housing being provided with a partition extending transversely thereof and providing compartments at either side of the same, of a shaft extending transversely of the compartment in advance of said partition, the walls of said compartment being provided with slots through which the ends of said shaft project, a motor arranged in the compartment in rear of said partition and having its armature shaft projecting through the partition, a saw mounted on said transversely extending shaft and adapted to be projected through the slot of said base, a U-shaped yoke arranged over said casing and spanning the same, the ends of said yoke being pivoted on the side walls of the housing and connected with the projecting ends of said transverse shaft, whereby to vary the degree of projection of the saw through the slot of the base upon movement of said yoke with respect to the housing, a segmental rack carried by the housing, and latching means carried by the yoke and co-operating with the segmental rack for locking the yoke in its different positions of adjustment, a train of gearing arranged in the compartment wherein the saw is located and affording driving connections between said transverse shaft and the armature shaft of said motor, and means carried by the housing for guiding the saw with respect to the work.

7. In a portable saw, the combination with a housing having an elongated base and provided with a slot therein, said housing being provided with a partition extending transversely thereof and providing compartments at either side of the same, a shaft extending transversely of the compartment in advance of said partition, the walls of said compartment being provided with slots through

In testimony whereof I affix my signature.

ALEX A. CLARKE.
